UNITED STATES PATENT OFFICE.

NATHANIEL SHAFFSTALL, OF FLINT, INDIANA.

PLOW.

SPECIFICATION forming part of Letters Patent No. 254,394, dated February 28, 1882.

Application filed December 7, 1881. (No model.)

To all whom it may concern:

Be it known that I, NATHANIEL SHAFFSTALL, a citizen of the United States of America, residing at Flint, in the county of Steuben and State of Indiana, have invented certain new and useful Improvements in Plows; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to plows; and it consists in the construction and arrangement of the several parts, as will be hereinafter fully set forth.

In the drawings, Figure 1 is a side elevation; Fig. 2, a sectional view of the frame-work with the plow attached thereto; Fig. 3, a top plan view, and Figs. 4, 5, and 6 are details. Fig. 7 is a vertical longitudinal section, looking from the left side of the plow.

AA are the wheels. The spindles are formed upon the lower ends of the vertical slotted axle-plates aa, as shown.

The axle-frame consists of the horizontal cross-plate b, which has its ends bent downwardly, forming the angle-plates b', the lower ends of which are slotted and are secured to the slotted plates aa by suitable bolts, and is capable of being set at different heights upon them, as shown.

Attached to the upper horizontal sides of the angle-plates b' is the frame C. Its forward end extends in front of the axle-frame and affords means of attachment for the tongue-hounds. The right frame-bar C extends backwardly from the frame b. Its rear end is curved downwardly, and has pivoted to it the small wheel D, as shown. The left frame-bar C extends backwardly to the point where the right rod commences to curve, where it is bent upwardly and carried across to the right frame-bar and secured to its sides, as shown.

Extending from the point where the left frame-rod C bends upward to the lower end of the right rod C is a guard-rail, e, which prevents the plow from getting out of place.

Journaled between the horizontal sides of the axle cross-plate b is the elevating crank E.

Its right end projects beyond the frame b, and has placed upon its end the grooved pulley e. Pivoted centrally upon the crank is the connecting-bar e', the lower end of which is firmly secured to the top of the plow-beam F, as shown. Pivoted to the right frame-rod C is the lever G. The chain g has one end secured to the bottom of this lever, is carried around the grooved pulley e, and is attached to the lever above the pivot-point, as shown. To prevent slipping the chain is made fast to the pulley by a pin, as shown.

Secured to the rear end of the plow is the chain g', which passes over a pulley, g², on the right frame-rod C, and is attached by a hook upon its end to a ring in the lower end of the lever G, as shown. By this arrangement of the chains and lever the point of the plow can be raised or lowered, or it can be raised entirely out of the ground. When the plow is in the ground and at work the chain g' is unhooked from the lever G and caught over the top of the frame-work. The plow can then be ranged at different depths by the lever G. When it is desired to raise the plow entirely out of the ground the chain g' is hooked to the lever G, which is then carried backward, and the front and rear of the plow are elevated together.

Placed around the crank E, between the pulley e and the side of the arch b, is a ratchet-wheel, e², the teeth of which engage with a projection upon the end of the lever e³, which is pivoted at e⁴ to the top of the frame C, as shown. The foot-rest e⁵ extends beyond the pivotal point, and the downward projection e⁶ permits the lever to rise sufficiently to clear the ratchet teeth. The lever falls into position by its own weight, or a spring may be placed under its rear end. The forward ends of the frame-rods C are curved slightly upward, and form a loop in their ends, as shown.

HH are hounds. They have loops upon their inner ends, through which and the loops in the forward end of the frame C passes the rod h. A cross-bar, h', extends across the inner ends of the hounds to brace them.

I is the tongue. It is pivoted, as shown, to the forward end of the hounds, and its inner end extends backward to the bar h', and has formed in its inner end a vertical slot, i, as shown. Pivoted centrally to the bar h' is the

L-shaped lever i' . Its forward arm extends over the tongue and its end is bent downwardly into the slot i , as shown. The other arm extends along the bar h' , its end projecting beyond the hounds, and has pivoted to it the connecting-rod i^2 , the other end being pivoted to the lever K , which is pivoted to the left frame-bar C , and ranges along a curved rack, k , which is secured to the top of the frame-bar, 5 as shown. In the operation of the plow it will be seen that by fixing the lever K at different points along the rack k the inner end of the tongue can be swung to the right or left, as desired, thus regulating the width of the furrow 10 at will.

What I claim is—

1. The combination, in a sulky-plow, of the arched frame b , the crank E , journaled therein, the grooved pulley e , the bar e' , connecting the 20 crank to the front end of the plow-beam, and the lever G , provided with a chain, g , substantially as shown and described.

2. In a plow, the combination, with the frame and plow-beam, of the connecting-bar and crank $E e e'$ and the lever G , having its chain g , attached to its lower end, passed around pulley e and secured to the lever above its fulcrum, and also provided with chain g' , attached to the rear end of the plow and passing over pulley g^2 , substantially as and for the purposes shown 25 and described.

3. The combination of the plow-beam, its vertical bar e' , the crank E , and its pulley e , with the lever G , chain g , adapted to operate the forward end of the plow, and the chain g' , 30 passing over the pulley g^2 and adapted to operate the rear end of the plow, substantially as shown and described.

In testimony whereof I affix my signature in presence of two witnesses.

NATHANIEL SHAFFSTALL.

Witnesses:

JOSEPH A. WOODHULL,
EDWARD G. WALLS.
